US0D1101829S

(12) **United States Design Patent** (10) **Patent No.:** **US D1,101,829 S**
(45) **Date of Patent:** **** Nov. 11, 2025**

(54) **CUTTING INSERT FOR MACHINE TOOLS FOR METALWORKING**

(71) Applicant: **KORLOY INC.**, Seoul (KR)

(72) Inventors: **Sung Hun Kim**, Chungcheongbuk-do (KR); **Young Heum Kim**, Chungcheongbuk-do (KR); **Tae Hee Cho**, Chungcheongbuk-do (KR); **Ki Chan Nam**, Chungcheongbuk-do (KR)

(**) Term: **15 Years**

(21) Appl. No.: **35/522,351**

(22) Filed: **Jul. 31, 2024**

(80) **Hague Agreement Data**

Int. Filing Date: **Jul. 31, 2024**

Int. Reg. No.: **DM/239960**

Int. Reg. Date: **Jul. 31, 2024**

Int. Reg. Pub. Date: **Sep. 20, 2024**

(30) **Foreign Application Priority Data**

Mar. 18, 2024 (KR) 30-2024-0010298

(51) **LOC (15) Cl.** **15-09**

(52) **U.S. Cl.**

USPC **D15/139**

(57) **CLAIM**

The ornamental design for a cutting insert for machine tools for metalworking as shown and described.

DESCRIPTION

1. Cutting insert for machine tools for metalworking

1.1 : Perspective

1.2 : Front

1.3: Back

1.4: Top

1.5: Bottom

1.6 : Left

1.7 : Right

1.8 : Perspective from a bottom view

1 Claim, 8 Drawing Sheets
